UNITED STATES PATENT OFFICE

2,403,173

WATER HEATING UNIT

Max Doerner, New York, N. Y.

Application December 29, 1944, Serial No. 570,312

1 Claim. (Cl. 122—250)

1

This invention relates to water heating coils for use with steam boilers, gas boilers, and other appliances where it is desired to preheat the water by waste heat to increase the efficiency of the apparatus in connection with which the coils are employed and is an improvement over the heating unit disclosed in Patent #1,860,495, issued to me on May 31, 1932.

It is one of the principal objects to provide a heating coil unit adapted to be used with various types of heaters;

Another object is to make a unit of this character easily applicable to various kinds of heaters;

A further object is to attain the desired purpose with a coil which is economically manufactured and which operates at a high efficiency;

Still further objects will become apparent as the nature of the invention is better understood after a perusal of the following specification.

The invention is illustrated by the accompanying drawing in which a preferred embodiment of the invention is shown, and in which

Fig. 1 is a plan view of the coil unit; and

Fig. 2 is an elevational view of the same, partly in section.

In both of these figures the conventional design of a steam boiler is shown in dotted lines to indicate the manner in which the unit is attached to apparatus of that kind.

10 is the outer cylindrical shell of such a boiler, having a water and steam space 11 formed by a top wall 12, a bottom wall 13, and a cylindrical inner shell 14 defining a waste gas passage 15 communicating with a fire box 16 below the passage and the bottom wall 13. The upper ends of shell 10 are extended above the top wall 12 and are adapted to receive a dome 17 having a flue connection at 18. Only the vital elements of a boiler have been described so far to illustrate the application of the invention which is in no way limited to any particular type.

Referring now to the essential parts of the invention, 19 is the inlet end of a heating coil having a union connection 20 for ready application to a water supply pipe. 21 are a plurality of coils horizontally disposed on top of top wall 12 of the steam space of the boiler. The inner end of coils 21 is bent downwardly at 22 and is coiled downwardly alongside the walls 14 of firebox 16 to form an outer coil 23. The bottom end of this coil is bent upwardly at 24 to form an upwardly extended coil 25 within the convolutions of coil

23. The top end of coil 25 is bent over at 26 and passes over coils 21 and extends outwardly of the

boiler shell to terminate in an outlet end 27 having a union connection 28 which is attached to a water outlet pipe.

In operation, water is admitted into the heating coil at 19, whence it first passes through the plurality of coils 21 on top of the top wall 12 of the steam space of the boiler. These coils 21 absorb a good deal of heat from the wall 12. The water then passes downwardly into the outer coil 23 which extends through the waste gas passage 15 and is heated further by the gases arising from the firebox 16. Then the water is led upwardly again through inner coil 25 to be further heated, and finally through union connection 27 to a boiler feed pipe shown in dotted lines in Fig. 2.

During this travel the water is thus heated in three different stages, firstly, in the horizontally disposed coils, above and immediately adjacent the hot top wall of the boiler, secondly, in the outer coil located in the waste gas passage, and thirdly, in the inner coil also located in this passage. This results in a preheating of water by otherwise wasted heat which greatly increases the efficiency of the boiler or other apparatus to which the coil unit is applied.

25 The union connections at both the inlet and outlet ends of the coil make application and removal of the coil particularly simple.

While I have shown the invention applied to 30 a steam boiler, as stated above, this is for illustration's sake only. The heating coil unit can be applied to gas ovens, furnaces, or any other apparatus where it is desired to heat, respectively, preheat the water effectively. It can also be employed in connection with a separate gas heater used only to create heat to raise the temperature of the water in the coil, when the shape of the gas heater need only be made so as to support the top coils of the unit and provide 35 a heat outlet into which the downwardly and upwardly extending coils project.

Instead of the vertical inside coil, the water may be led upwardly in a straight pipe or a pipe having only slight convolutions.

45 Instead of completing a plurality of circular coils and then connecting them to the downwardly and upwardly extending center coils to connect the center coils directly to a boiler feed pipe, I may provide a plurality of half coils on top only 50 to connect to the center coils and then connect the outlet of the center coils to another plurality of half coils on top which then connects with the boiler feed pipe.

The center coils instead of being made of one piece with the circular top coils, may be union

or couplings be connected to the top coils, if found expedient for replacing the center coil.

Various other changes in form, proportions and minor details of construction may be resorted to without departing from the principle or sacrificing any of the advantages of the invention as defined in the appended claim.

What I claim as new, is:

In a steam boiler including a structure having a firebox, a flue connection, a duct between the firebox and flue connection forming a waste gas passage, a chamber around said duct for water and generation of steam, a water heating unit comprising a plurality of horizontally disposed coils of pipe having an inlet, a plurality of ver-

5 tically descending coils of pipe connected to said horizontally disposed coils, and a plurality of vertically ascending coils of pipe concentric with, and forming the continuation of the lowest coil of, said plurality of coils of descending pipe, said vertically ascending coils of pipe having an outlet, and a union connection at, respectively, said inlet and said outlet, said inlet being connected to the feed water supply for the boiler, and said outlet being connected to the bottom of said chamber, the said horizontally disposed coils being disposed on top of said chamber forming a support for the unit, said descending and ascending coils being located in said waste gas passage.

MAX DOERNER.
